United States Patent Office

Des. 202,390
Patented Sept. 21, 1965

202,390

PORTABLE DUPLICATOR

Harold F. Arndt, 1320 S. Del Mar Ave.,
San Gabriel, Calif.

Filed June 1, 1964, Ser. No. 80,223

Term of patent 14 years

(Cl. D64—11)

FIG. 1

FIG. 4

FIG. 2

FIG. 5

The side not shown is the same in appearance as the side shown.

I claim:

The ornamental design for a portable duplicator, as shown and described.
